CLAIM

The ornamental design for a power connector for artificial tree lighting as shown and described.

DESCRIPTION

FIG. 1 is a perspective view of the power connector for artificial tree lighting;

FIG. 2 is a front view of FIG. 1 thereof;

FIG. 3 is a back view of FIG. 1 thereof;

FIG. 4 is a right side view of FIG. 1. The left side being a mirror image thereof;

FIG. 5 is a top view of FIG. 1 thereof; and,

FIG. 6 is a bottom view of FIG. 1 thereof.

The areas shown within the solid lines and adjacent the broken lines, as well as all areas within the broken lines in FIG. 6 are understood to form no part of the claimed design. The broken line portions in the figures illustrate the portions of the design that form no part of the claimed design.
